[57] CLAIM

The ornamental design for a cursor controlling pen, as
shown and described.

DESCRIPTION

FIG. 1 is a perspective view of a cursor controlling pen
showing my new design;
FIG. 2 is a top plan view thereof;
FIG. 3 is a bottom plan view thereof;
FIG. 4 is a side elevational view thereof, the opposite
side being a mirror image;
FIG. 5 is a front elevational view thereof; and,
FIG. 6 is a rear elevational view thereof.
